His Attorney.

UNITED STATES PATENT OFFICE.

JOHN A. SEEDE, OF SCHENECTADY, NEW YORK, ASSIGNEE TO GENERAL ELECTRIC COMPANY, A CORPORATION OF NEW YORK.

ELECTRIC FURNACE CONTROL APPARATUS.

1,253,732.

Specification of Letters Patent. Patented Jan. 15, 1918.

Application filed June 21, 1917. Serial No. 176,213.

To all whom it may concern:

Be it known that I, JOHN A. SEEDE, a citizen of the United States, residing at Schenectady, in the county of Schenectady, State 5 of New York, have invented certain new and useful Improvements in Electric Furnace Control Apparatus, of which the following is a specification.

The present invention relates to electric 10 control apparatus for electric furnaces, particularly for arc furnaces. The object of my invention is to provide means whereby the length of the arcs and current flowing in the arcs may be maintained uniform.

15 In my U. S. Patent #1,206,603 of November 28, 1916, is described an electric furnace control apparatus whereby motors connected to the electrodes are actuated by electrical switching means responsive to variations of 20 current, or other electrical conditions of the energy supply circuit.

In accordance with my present invention certain advantages hereinafter specifically explained are secured by regulating one arc 25 of a furnace in accordance with current variations, and regulating another arc in the same circuit in accordance with voltage variations.

Referring to the drawing, the furnace is 30 diagrammatically indicated by a rectangle 1, shown in dotted outline, and comprises a stationary conductor or electrode 2 located at the base of the furnace, and movable electrodes 3, 3' adapted to support arcs in series 35 in conjunction with the stationary electrode 2. These electrodes may either all consist of carbon or graphite, or in some cases, the conductor 2 may be a charge of metal or other conductive material in the furnace. A

40 motor 4 is mechanically connected to the electrode 3 by any form of suitable gearing, the drawing showing a speed reducing gear 5 driven by the motor acting on a nut 6 on the screw threaded rod 7 to raise and lower 45 the electrode. The motor connected to the electrode 3' has not been shown. The electrode is shown as connected to a gearing 8 and it is to be understood that this gearing is connected to a motor and its control apparatus similarly to the motor and control 50 apparatus shown in connection with electrode 3.

The electrodes 3 and 3' are connected respectively to electric mains 9 and 10 receiving electric energy from the secondary of a

transformer 11. A relay magnet 12 is connected to the secondary of a current transformer 13, the primary of which is constituted by a portion of the conductor 9. The armature 14 of the relay 12 is connected to 60 a lever 15 operating to make contact with either conductors 16 or 17 to complete a separate circuit and thereby to energize either of relay magnets 18 and 19, as will be hereinafter described in greater detail. 65 These magnets in turn control the armature circuit of the motor 4 to raise or lower the electrodes in order to maintain the current in an arc between the electrodes 3 and 2 substantially constant. The winding of a second relay 20 is connected respectively to the conductor 10, which supplies the electrode 3' and to a conductor 21 which is connected to the electrode 2, thus being responsive to voltage variations of an arc operating between the electrodes 2 and 3'. An adjustable 70 resistance 22 in circuit with the winding of the relay 20 permits the setting of the magnet to be made as desired. The armature 23 of the relay 20 is connected to a switch lever 75 24, adapted to contact with either of the conductors 25 or 26 connected to a set of relays and contactors controlling the motor (not shown) for moving the electrode 3'.

By this system of control one series arc 80 being controlled by current variations and a second series arc by voltage variations, uniformity and regularity of arc length and heat intensity is obtained or the heats of the respective arcs are maintained at desired 85 unequal values. At the beginning of the operation the movement of the electrodes is controlled by hand to strike the arcs, and their operation then continues automatically.

When the furnace is energized the relay 90 27 pulls up its armature and causes the switch lever 28 to complete a circuit between the conductors 29 and 30. In case the energy supply is interrupted the contactor 27 releases and opens the circuit to safeguard 95 the apparatus against injury.

In case the current in an arc between the electrodes 3 and 2 is too low the current-responsive magnet 12 completes a circuit from the conductors 31, 32, which are preferably 100 supplied with direct current to energize the relay magnet 19, the circuit being through the conductors 29, 30, switch lever 15, conductors 16 and 33. The magnet 19 pulls up 105 its armature 34, closes contact 35 and 36, and 110

energizes the motor 4, the motor circuit being through the conductor 37, resistance 38, contact 35, conductor 39, the armature of the motor, conductors 40, 41, contact 36, and the conductor 33. The motor is connected to thereupon lower the electrode 3, thereby increasing the current until the contactor 15 releases and breaks the circuit of the magnet 19.

10 As the two arcs are in series, the current will increase between the electrodes 3' and 2, as well as between the electrodes 3 and 2 and if the former electrodes are too far apart, the voltage drop between them will be too great, and the voltage-responsive relay 20 will be energized to contact with the conductor 26 and set into operation a motor (not shown) to lower the electrode 3' the control apparatus being like the apparatus 15 energized by the current-responsive contactor 12 and being omitted to simplify the drawing. The reverse operation when, for example, the current is too great, will cause the electrodes to be raised.

20 25 In that case, the armature 14 of the magnet 12 is pulled down causing the switch lever 15 to contact with the conductor 17 completing a circuit through the relay magnet 18, by way of conductors 42 and 33. The 30 motor 4 is thereupon energized to revolve in the opposite direction to raise the electrodes, the circuit being by way of the conductors 33, 42, contact 43, conductors 43', 39, 40, contact 44, conductor 45, resistances 46 35 and 38 and the conductor 37.

When the electrodes have been raised or lowered to a point which results in a change of current or voltage causing the contactor to open the motor is brought to a stop by 40 dynamic braking in the following manner. The counter-electromotive force of the mo-

tor energizes a magnet 47 connected across the conductors, and by the closure of the contact 48, assisted by the spring 49, inserts a resistance 50 in the armature circuit to 45 quickly bring the motor to rest, as well understood. While the motor circuit is closed through the resistance 50, a mechanical interlock 51 prevents the closure of the relay magnets 18 and 19, which are attached respectively to interlocks 52 and 53.

What I claim as new and desire to secure by Letters Patent of the United States, is:—

1. The combination of a plurality of electrodes adapted to support a plurality of 55 arcs, electrical connections therefor, means for regulating the length of one of said arcs in response to variations of current in the circuit of said arc, and means for regulating another arc in response to variations of voltage across the terminals of said arc.

2. An electric furnace control apparatus comprising arc-supporting electrodes to be regulated, motors operatively connected respectively to each of said electrodes, energy 65 supply conductors connected to said electrodes, means for controlling a motor connected to one electrode in response to current changes in the supply circuit of the corresponding electrode to move said electrode in a direction whereby a desired current value is maintained, means for controlling a motor connected to another electrode in response to voltage changes across an arc supported by said electrode to move said electrode in a direction whereby a desired voltage drop is maintained, and means for braking said motors when the desired regulation has been attained.

In witness whereof, I have hereunto set my hand this 20th day of June, 1917.

JOHN A. SEEDE.
